UNITED STATES PATENT OFFICE.

JAMES GORDON, OF CHICAGO, ILLINOIS.

DESIGN FOR A SCORE-PAD HOLDER.

Application filed January 25, 1928. Serial No. 25,019. Term of patent 3½ years

To all whom it may concern:

Be it known that I, JAMES GORDON, a citizen of the United States, residing at Chicago, in the county of Cook and State of Illinois, have invented a new, original, and ornamental Design for a Score-Pad Holder, of which the following is a specification, reference being had to the accompanying drawing, forming a part thereof.

The figure is a perspective view of the score pad holder showing my new design.

I claim:

The ornamental design for a score pad holder substantially as shown.

JAMES GORDON.
